UNITED STATES PATENT OFFICE.

JAMES E. HUTCHINS, OF BUFORD, GEORGIA.

SLOT MACHINE.

Application filed September 24, 1924. Serial No. 739,696.

The device forming the subject matter of this application is a coin-controlled vending machine including a delivery mechanism and a coin controlled mechanism. And the 5 object of the invention is to improve the delivery mechanism.

It is within the province of the disclosure to improve generally and to enhance the 10 utility of devices of that type to which the invention appertains.

With the above and other objects in view, which will appear as the description proceeds, the invention resides in the combination and arrangement of parts and in the 15 details of construction hereinafter described and claimed, it being understood that, within the scope of what is claimed, changes in the precise embodiment of the invention shown, can be made, without departing from 20 the spirit of the invention.

In the drawings:

Figure 1 is a front elevation showing a device constructed in accordance with the invention; Figure 2 is a section on the line 25 2—2 of Figure 1; Figure 3 is a vertical section taken through the body portion of the cabinet; Figure 4 is a sectional view, the cutting plane in Figure 4 being at right angles to the cutting plane in Figure 3; Figure 5 is a section taken on the line 5—5 of Figure 4, parts being omitted; Figure 6 is a vertical sectional view showing the rack and attendant parts, portions being broken away; Figure 7 is a horizontal section taken 30 through that part of the machine which appears in Figure 6; Figure 8 is a diagram showing the operating lever in the position which it will assume with respect to the star wheel, Figure 9 is a diagram showing another 35 of the levers and the shaft with which it operates, and Figure 10 is a diagram disclosing the delivery rack, in part, Figures 8, 9 and 10 being supplemental to each other, and showing certain parts of the machine as 40 they will appear at one step in the operation; Figures 11, 12 and 13 are diagrams showing, respectively, the parts delineated in Figures 8, 9 and 10, the parts having been shifted to a position different from that shown 45 in Figures 8, 9 and 10, Figures 11, 12 and 13 supplementing each other; Figures 14 and 15 are diagrams illustrating the parts 50 depicted in Figures 11 and 12, those parts having been shifted to another position from 55 that shown in Figures 11 and 12, Figures

14 and 15 supplementing each other; Figure 16 is a perspective showing a part of the coin controlled mechanism; Figure 17 is a perspective showing the latch; Figure 18 is a sectional view of the coin chute and attendant parts; Figure 19 is a cross section taken through the block which forms part of the coin controlled mechanism; Figure 20 is a longitudinal section taken through that 60 part of the device which appears in Figure 18. 65

In carrying out the invention, there is provided a cabinet, which is denoted by the numeral 1, the cabinet comprising a back 2, a bottom 3, an end 4, an end 5, a top 6, a partition 7 extended between the ends 4 and 5 and disposed parallel to the back 2, and a table 8 extended between the ends 4 and 5, and forwardly from the back 2, the lower edge of the partition 7 being spaced from 70 the upper surface of the table 8. A lower front piece 9 extends upwardly from the bottom 3 and cooperates with the ends 4 and 5 of the cabinet. A plate 10 extends between the ends 4 and 5 and cooperates with 75 the bottom 3, there being a compartment 11 between the plate 10 and the front piece 9. The merchandise to be dispensed may be permitted to drop into the compartment 11, although, as hereinafter explained, a rack is 80 provided for receiving the merchandise before it drops into the compartment, it being optional to use or omit the rack. A cross bar 12 extends between the ends 4 and 5 of the cabinet and is located slightly above 85 90 and in front of the table 8. The cabinet 1 includes a box-like extension 16 projecting from the end wall 4 of the cabinet. A partition 17 extends between the end wall 4 and the outer wall of the extension 16 and forms 95 a money receptacle 18, access to which is had by way of a hinged and locked door 19. Strips 20 are vertically mounted on the ends 4 and 5 of the cabinet 1 and cooperate with the partition 7 to form guides 21 wherein the 100 merchandise to be dispensed is carried, the merchandise, in the present instance, being in the form of lead pencils, although the machine may be used for dispensing merchandise of any kind. The pencils 22 may be 105 placed in the guides 21 readily, because the cabinet 1 has a hinged front door 23.

A bracket 24 (Figures 3 and 5) extends rearwardly from the partition 7. An angular or bell crank lever 26 is fulcrumed on 110

the bracket 24 and includes a short horizontal arm 27 and a long depending arm 28, the arm 28 of the lever being mounted to move in the guide 29 (Figures 3 and 4) on the partition 7.

An ejector 30, in the form of a plate, is mounted to slide on the table 8 beneath the lower edge of the partition 7, and beneath guides 31 secured to the ends 4 and 5 of the cabinet 1, the forward ends of the guides 31 extending beneath a combined cleat and stop 32 (Figures 3 and 4) mounted on the partition 7. The table 8 has an opening 33 through which extend forks 35 (Figure 4) on the lower end 38 of the lever 26, the ejector 30 having a notch 34 in its rear edge, through which the forks 35 pass. A finger 36 is disposed parallel to the ejector 30, and is carried by a bracket 37 mounted on the ejector 30, the bracket being adapted to cooperate (Figure 3) with the stop or cleat 32 when the ejector 30 moves forwardly into the position shown in Figure 3. There is a longitudinal slot 38 in the finger 36, receiving a pivot element 39 mounted in the forks 35 of the arm 28 of the lever 26.

A rod or support 40 is mounted in the ends 4 and 5 of the cabinet 1, and on the rod 40, levers 41 are fulcrumed intermediate their ends, the levers having diverging upwardly extended arms 42 prolonged forwardly with respect to the plate 10 and the table 8, as shown in Figure 3. The levers constitute a rack on which the ejected lead pencil or other merchandise is received. There are slots 43 in the rear ends of the levers 41, the slots receiving a pivot element 44 carried by the forks 35 of the arm 28 of the lever 26. Retractile springs 45 are connected (Figure 5) to the short horizontal arm 27 of the lever 26, at their upper ends, the lower ends of the springs 45 being anchored on the ends 4 and 5 of the cabinet 1, or elsewhere.

A shaft 46 (Figures 3, 4, 9, 12 and 15) is journaled in the ends 4 and 5 of the cabinet 1, and one end of the shaft 46 projects into the extension 16 of the cabinet, as indicated in Figure 2. Saving at its ends the shaft 46 is of rectangular cross section. The shaft 46 may be mounted to rotate in bearings 47 on the ends 4 and 5 of the cabinet 1.

That end of the shaft 46 which projects into the extension 16 carries a star wheel 49 provided with projections, certain of the projections being marked by the numerals 50 and 51, in order to facilitate the explanation of the operation of this part of the machine. A lever 52 (Figure 2) is fulcrumed intermediate its ends at 53 on a bracket 54 carried by the end wall 4 of the cabinet and located in the extension 16. The lever 52 is adapted to swing vertically in a slot 55 (Figure 1) formed in a plate 56 mounted

on the front portion of the extension 16. The lever 52 slides in contact with a wear plate 57 (Figure 2) mounted on the end wall 4. The lower end of a retractile spring 58 is connected to the lever 52, the upper end of the spring being attached to the end 4 of the cabinet. Noting particularly Figures 8, 11 and 14, it will be observed, in conjunction with Figure 2, that the lever 52 is provided at its inner end with a head 59 having a concaved cam edge 60 below which is located a notch 61 forming a shoulder 62, there being a recess 63 in the head 59, the recess being located below the shoulder 62. The U-shaped support 64 (Figure 7) is carried by the lever 52 and projects into the extension 16. The support 64 receives an arcuate rack 65 attached to the end 4 of the cabinet, the rack having teeth 66, and being provided with an enlarged upper recess 67 (Figure 6) and with an enlarged lower recess 68. A shaft 69 is mounted on the support 64, and a pawl 70 is mounted to swing on the shaft 69, the pawl being adapted to cooperate with the teeth 66 of the rack 65. In order to hold the pawl 70 at right angles to the rack 65, under conditions which will be pointed out hereinafter, any suitable spring means may be provided. If desired, the shaft 69, as shown in Figure 7, may be surrounded by torsion springs 71, the outer ends of the springs being connected to the support 64, and the inner ends of the springs being connected to the pawl 70.

At this point, the description of the structure will be suspended, in order to explain the operation of the delivery mechanism, and when that has been done, the coin-controlled features will be taken up.

In practical operation, the ejector 30 is advanced, as shown in Figure 3, and the lowermost piece of merchandise 22 rests on the ejector, behind the cross bar 12. The outer end of the lever 52 is swung downwardly, the spring 58 being put under tension. Noting Figure 6, it will be observed that when the lever 52 is swung downwardly, the pawl 70 can click over the teeth 66 of the rack 65. Ultimately, the inner end of the pawl 70 arrives in the lower recess 68, and, then, the springs 71 swing the pawl 70 until it stands at right angles to the rack 65. The lever 52 then can be moved upwardly until the pawl arrives in the upper recess 67, whereupon the springs 71 dispose the pawl 70 at right angles to the rack bar 65, and, then, the lever can be swung downwardly. When the pawl 70 is in the position shown in Figure 6, the lever 52 cannot be moved upwardly, and after the lever 52 has been moved downwardly far enough so that the pawl 70 is in the recess 68, and then has been moved upwardly, along with the lever 52, the lever cannot be moved downwardly, the length of the pawl

70 being greater than the distance between the center of suspension of the pawl and the base of the teeth 66 in the rack bar.

Dismissing the pawl 70 with the foregoing explanation, let it be assumed that the outer end of the lever 52 is moved downwardly, the head 59 of the lever moving upwardly (note Figure 8). First, the shoulder 62 on the head 59 of the lever engages a tooth 50 and rotates the star wheel 48 and the shaft 46 until the arm 27 of the lever 26 rests (Fig. 12) on the one of a plurality of fingers 72 wherewith the shaft 46 is provided. When the shaft 46 is rotated, and when the lever 26 is tilted from the position shown in Figure 9 to the position shown in Figure 12, the springs 45 are extended, and the arm 28 of the lever 26 pulls the ejector 30 until the lowermost piece of merchandise 22 (Figure 3) rests on the table 8, in front of the ejector, the pivot element 39 in the forks 35 of the arm 28 of the lever 26, moving rearwardly to the end of the slot 38 in the finger 36 which is attached at 37 to the ejector 30. When the arm 28 of the lever 26 swings from the position shown in Figure 9 to the position shown in Figure 12, the pivot element 44 in the forks 35 of the arm 28 of the lever 26 moves in the slot 43 of the levers 41 and tilts the levers until the arms 42 are raised from the position shown in Figure 3 to receive the lowermost piece of merchandise 22 when the same is moved forwardly by the ejector 30.

When the machine goes out of the shop, it is supplied with the levers 41, and also with an upper piece 14 which extends downwardly and forwardly from the bar 12, there being an opening 15 in front of the part 14, so that access may be had to the compartment 11. It is then optional with the user either to take off the levers 41, let the plate 14 remain, and have the ejector 30 push the pencil off into the compartment 11: or to take off the plate 14, let the levers 41 remain, and have the ejector 30 push the pencil off into the arms 42 of the levers 41, as above explained.

The description of the operation now supposes the ejector 30 to have been retracted, ready to eject the lowermost piece of merchandise, the star wheel 48 having been rotated by the engagement between the shoulder 62 of the lever 52 and the tooth 50, the tooth 51 of the star wheel being disposed in the recess 63 of the head 59 of the lever 52, as shown in Figure 11. The outer end of the lever 52 is swung upwardly, and the head 59 moves downwardly, from the position shown in Figure 11, the end of the tooth or projection 50 on the star wheel 48 traversing the cam edge 60 of the head 59 of the lever 52, as shown in Figure 14, clockwise rotation being imparted to the star wheel 48 and the shaft 46, the finger 72 on

the shaft 46 being withdrawn from engagement with the arm 37 of the lever 26, as shown in Figure 15. The springs 45 of Figure 4 cause the end 27 of the lever 26 to move downwardly along the uppermost 70 finger 72 in Figure 15, until the part 27 rests on the shaft 46, as shown in Figure 9, a sudden rotation being imparted to the shaft 46, and the springs 45 reacting on the lever 26 to swing the arm 28 forwardly, the 75 ejector 30 being carried forwardly, the lowermost piece of merchandise 22 being received in the arms 42 of the rack, and the arms 42 being lowered into the position shown in Figure 3. The tooth 51, during the operation above mentioned, will have moved from the position shown in Figure 14, into the position occupied by the tooth 50 in Figure 8, and the machine is ready for another operation. 80

Having thus described the construction and the operation of the delivery mechanism, the construction of the coin control will next be considered.

The upper end of a coin expelling plunger 73 is connected at 74 to the lever 52, the plunger having an offset keeper 75, the plunger being mounted to slide in a longitudinal slot 76 formed in a block 77 secured at 78 to the end 4 of the cabinet 1. Adjacent to its lower end, the block 77 has an inclined shoulder 79 adapted to discharge the expelled coin into the coin receptacle 18. Above the shoulder 79, the block has a notch 80. The block 77 has a notch 81, there being a fixed coin stop 82 on the block, between the notches 80 and 81. A coin chute 83 extends through the wall of the extension 16 and discharges into the notch 81. The block 77 has a recess 84 disposed opposite to the fixed coin stop 82. The numeral 85 designates a latch, the lower end of which is pivoted at 86 on the block 77. The inner edge of the latch 85 is provided with a seat 87 adapted to receive the keeper 75 on the plunger 73. 100 On the inner surface of the latch 85 there is a coin stop 88 adapted to cooperate with the coin stop 82, the coin stop 88 being movable in the recess 84 of the block 77. One end of a retractile spring 89 is connected to the latch 85, at a point near to the upper end of the latch, the other end of the spring being anchored on the coin chute 83 or elsewhere. The spring 89 tends to swing the upper end of the latch 85 inwardly, until, as shown in Figure 18, the inner edge of the latch rests against the keeper 75 on the plunger 73. A retaining strip 90 for the coin extends longitudinally of the block 77 and is secured to the block as shown at 91 and at 115 92. The securing element 92, and an additional securing element 93 retain a transverse guide 94 on the block 77, the plunger 73 being mounted to reciprocate behind the 120 guide 94, as clearly indicated in Figure 20. 130

Suppose that no coin has been introduced into the chute 83. It will now be obvious that if an attempt is made to swing the lever 52 downwardly, the plunger 73 will be carried downwardly a short distance, the keeper 75 on the plunger 73 being received in the seat 87 of the latch 85, the upper end of the latch being swung to the right in Figure 18, by the spring 89. The machine, therefore, 10 cannot be operated. Let it be supposed however, that when the parts are disposed as indicated in Figure 18, a coin 95 is deposited in the coin chute 83. The coin then rolls along the coin chute 83, through the 15 notch 81 in the block 77, behind the retaining strip 90 and behind the latch 85, the coin 95 resting in contact with the fixed coin stop 82 on the block 77, and in contact with the coin stop 88 on the latch 85, as 20 indicated in Figure 18. The upper end of the latch 85 now is prevented by the coin 95 from swinging to the left in Figure 18, under the action of the spring 89, and the plunger 73 may be moved downwardly with- 25 out causing the keeper 75 on the plunger to engage the seat 87 of the latch 85. In view of the foregoing, it will be obvious that the lever 52 may be swung downwardly, to operate the machine, if a coin has been de- 30 posited in the coin chute 83. The keeper 75 ultimately engages the coin 95 and pushes the coin downwardly, free of the stops 82 and 88, the coin striking the inclined shoulder 79 and rolling along the said shoulder into the coin receptacle 18.

Having thus described the invention, what is claimed is:

1. A delivery device for merchandise, comprising a slidable merchandise ejector, a lever fulcrumed intermediate its ends, means for connecting one end of the lever to the ejector, a shaft supported for rotation and having a projection co-operating with the other end of the lever to retract the ejector, 40 spring means for advancing the ejector, and means for rotating the shaft intermittently, first to operate the lever by way of the projection, and then to free the projection from the lever and to render the ejector responsive to the spring means.

2. A device of the class described, constructed as set forth in claim 1, and further characterized by the fact that the means for rotating the shaft embodies a star wheel

on the shaft, and a lever fulcrumed intermediate its ends and cooperating with the star wheel.

3. A device of the class described, constructed as set forth in claim 1, and further characterized by the fact that the means for rotating the shaft embodies a star wheel on the shaft, a lever fulcrumed intermediate its end and cooperating with the star wheel, a rack, an automatically reversible pawl on the lever and cooperating with rack to prevent retrograde movement of the lever when the lever is moved in opposite directions, and means for reversing the pawl when the lever arrives at opposite ends of its stroke.

4. A delivery device for merchandise, comprising a slidable merchandise ejector, a tiltable rack for receiving the ejected merchandise, and means cooperating with the ejector and the rack to raise the rack for the reception of the merchandise and to retract the ejector, and to advance the ejector and lower the rack.

5. A delivery device for merchandise, comprising a slidable merchandise ejector, a rack for receiving the ejected merchandise and pivotally mounted intermediate its ends, a lever and a fulcrum therefor, means for connecting the lever with the ejector, and a slidable connection between the lever and one end of the rack, the lever constituting 85 means for retracting the ejector and raising the other end of the rack, and for advancing the ejector and lowering said other end of the rack.

6. A delivery device for merchandise, comprising a slidable merchandise ejector, a rack for receiving the ejected merchandise and mounted for tilting movement, a lever and a fulcrum therefor, and pivot elements carried by the lever, the ejector and the rack having slots for the reception of the pivot elements, the slot of the rack permitting the lever to raise the rack before the retraction of the ejector begins, and being shorter than the slot of the rack to permit the lever to advance the ejector before the rack has been lowered to an appreciable extent.

In testimony that I claim the foregoing as my own, I have hereto affixed my signature.

JAMES E. HUTCHINS.
